BARREL MOUNTING ON A PIVOTED RECEIVER

Clarence E. Simpson, Wilbraham, Mass., assignor to the United States of America as represented by the Secretary of the Army

Application June 3, 1954, Serial No. 434,353

5 Claims. (Cl. 42—75)

This invention relates to firearms and more particularly to means for affecting the rapid replacement of barrels therein.

It is well-known that the barrels of automatic firearms become so overheated and damaged during continuous bursts of fire that they have to be replaced by another one. Where the firearm is mounted so that the barrel protrudes through a barrier, as in a tank, means have to be provided for the ejection of the hot barrel to the outside of the barrier and the installation of another barrel from the inside.

It is, therefore, an object of this invention to provide in an automatic firearm simple and reliable means for rapidly changing a barrel therein.

It is another object of this invention to provide in automatic firearms means for pivotally mounting the receiver thereof so that a barrel may be installed into the barrel jacket of the firearm from the rear end thereof.

It is still another object of this invention to provide in an automatic firearm having a pivotal receiver, fool-proof means for securing the operating parts in the receiver when rotated for the replacement of barrels.

It is a further object of this invention to provide in automatic firearms having a pivotal receiver, quick-change barrel means operated by the pivotal movement of the receiver.

It is a still further object of this invention to provide for automatic firearms, means in unitary relationship with the receiver for freeing a barrel from the barrel jacket and to move and lock another barrel therein at the proper headspace position.

The specific nature of the invention as well as other objects and advantages thereof will clearly appear from a description of a preferred embodiment as shown in the accompanying drawings in which:

Fig. 1 is a fragmentary partially cross-sectioned side view of a firearm in the recoil position;

Fig. 2 is a view taken along line 2—2 of Fig. 1;

Fig. 3 is a view taken along line 3—3 of Fig. 1;

Fig. 4 is a fragmentary partially cross-sectioned view of the firearm showing the barrel moved rearwardly by the receiver and, in phantom, the barrel ejected forwardly from the barrel jacket;

Fig. 5 is a fragmentary perspective view of the barrel locks in position to move the barrel to a locked position; and

Fig. 6 is a view similar to Fig. 5 but showing the barrel locks in position to move the barrel rearwardly.

Shown in the figures is a barrel jacket 12 having an upwardly open semicylindrical ledge portion 9 extending forwardly from the lower portion thereof, a receiver 13 pivotally mounted to barrel jacket 12 for upward rotation by a transverse pin 14 and a barrel 15 slidably mounted in the barrel jacket. Assembled within receiver 13 are operating parts (not shown) actuatable by a slide member 16 which is in a disconnect relationship with an operating rod 17 in barrel jacket 12 so as to permit piv-

otal, upward opening of the receiver. Receiver 13 is provided with an annular flange portion 18 which is matingly received by an extension portion 19 on the rear end of barrel jacket 12. Rotatably mounted through flange portion 18 is a transverse latch pin 20 having an external knob 21, a flat portion 22 extending between the inner walls of the flange portion and a semicylindrical portion 23 formed by flat portion 22. Pin 20 is so arranged that when in a latched position slide 16 and operating rod 17 reciprocate over portion 22 and when turned to an unlatched position semicylindrical portion 23 is moved upwardly to block forward movement of slide 16. Arcuate recesses 24 and 25 in the adjacent sides of slide 16 and operating rod 17, respectively, permit rotation of portion 23 when the firing mechanism of the firearm is in the recoil position. Extending forwardly from the rear side of extension portion 19 of barrel jacket 12 is a slot 26 arranged to permit slidable passage of portion 23 of pin 20, when in unlatched position, during the opening and closing of receiver 13. Slot 26 is terminated forwardly by a cylindrical hole 27 arranged to receive portion 23 when rotated downwardly to latched position wherein latch pin 20 is blocked from movement therefrom.

Provided on the inside of receiver 13 and integral therewith is a pair of laterally opposed barrel lock portions 28 which are in alignment with the longitudinal axis of barrel 15. Lock portions 28 are comprised of arm portions 29, which extend forwardly to flange portion 18, and lug portions 30 which extend inwardly therefrom. The front and rear sides of lugs 30, noted at 41 and 42, respectively, are arranged to be vertical with the longitudinal axis of barrel 15 when receiver 13 is latched to barrel jacket 12 and the lower rear corner of each lug 30 is cut to form a diagonal portion 31 to be further described hereinafter. The junction of diagonal portion 31 with rear side 42 forms corner 39 and the junction of the diagonal portion with the bottom side of the lug forms corner 40.

Barrel 15 is provided with a radially disposed pin 32 which is fixedly assembled, as by press fit, into a hole 33 provided in the outer wall of the barrel and is arranged to be slidably received in a longitudinal channel 34 along the top inner side of barrel jacket 12. Spaced from the breech end of barrel 15 is a pair of laterally opposed vertical chordal recesses 35 arranged to snugly receive lugs 30 therein when receiver 13 is latched to barrel jacket 12 and thereby securely lock the barrel to receiver 13 in battery position. Longitudinal chordal cuts 36 are arranged to receive arm portions 29 when lugs 30 are received by recesses 35 and extending forwardly from recesses 35 are triangular clearances 37 which form cam surfaces 38 which extend upwardly and forwardly from front side 41 approximately midway of the top side of lugs 30. The junctions of the front sides of recesses 35 and cam surfaces 38 form apex portions 43 and the junctions of the bottom sides of lugs 30 with front sides 41 thereof form pivotal portions 44.

Operation

When a barrel 15 is to be replaced in barrel jacket 12 the firing mechanism of the firearm is actuated to recoil position and then knob 21 is rotated to unlatched position wherein portion 23 of latch pin 20 is rotated upwardly to be received by slot 26. Thus, receiver 13 is free to be swung upwardly and, as has hereinbefore been explained, when pin 20 is in unlatched position portion 23 thereon blocks slide 16 from coming out of the receiver. During the initial rotation of receiver 13, the corners 39 press rearwardly against rear walls 45 of recesses 35 and during continued upward swing of the receiver such corners move along such walls to cammingly move barrel 15

rearwardly until diagonal portions 31 are parallel with walls 45. Thereafter, corners 40 cammingly engage walls 45 to continue camming barrel 15 rearwardly until lugs 30 are free of the barrel. In the meantime, the top portions of front sides 41 are rotated forwardly into clearances 37. It is clearly apparent that hereby considerable leverage is placed against barrel 15 to break any adhesion thereof with barrel jacket 12 as by carbon deposits produced during fire.

When receiver 13 is swung away from the breech of barrel 15, the barrel may be either pulled inwardly from barrel jacket 12 or pushed outwardly therethrough by another barrel. The forwardly projecting ledge 9 permits barrel 15 to tilt freely from barrel jacket 12 and drop therefrom without jamming.

The unused barrel 15 is installed in barrel jacket 12 so that pin 32 therein aligns with channel 34 in the barrel jacket and thereby aligns barrel locks 28 with recesses 35. When barrel 15 is pushed approximately into locked position in barrel jacket 12, receiver 13 is swung down whereby pivotal portion 44 engages cam surfaces 38 so that continued downward rotation of receiver 13 moves barrel 15 cammingly forward with diagonal portions 31 providing clearances to permit rotation of lug 30 past the junction of walls 45 of recesses 35 and the bottom sides of longitudinal cut 36. When receiver 13 is fully rotated downwardly, lugs 30 are snugly received by recesses 35 as hereinbefore explained to securely lock barrel 15 to receiver 13 in battery position.

It is clearly apparent from the foregoing that there is here provided a simple, rugged and reliable means for rapidly changing barrels in an automatic firearm.

Although a particular embodiment of the invention has been described in detail herein, it is evident that many variations may be devised within the spirit and scope thereof and the following claims are intended to include such variations.

I claim:

1. A firearm having a barrel jacket provided with a peripheral rearwardly extending portion, said portion being provided with laterally opposed slots which extend forwardly from the rear end thereof and being terminated by a larger cylindrical hole, a barrel slidably mounted in said barrel jacket, a ledge portion extending from the front end of said barrel jacket to assist in jam-free removal of said barrel therefrom, a receiver provided with a slide reciprocable into said barrel jacket, said receiver being mounted to said barrel jacket for pivotal movement between a closed position and an open position relative to said barrel jacket and being provided with a peripheral flange for receiving said portion when in said closed position, a pair of opposed barrel locking portions in said receiver provided with angular portions rotatably receivable in cooperating recesses in said barrel to securely lock said barrel to said receiver in battery position, cam surfaces in said recesses engageable by said angular portions for translation of pivotal movement of said receiver to rearward or forward movement of said barrel, and a latch pin mounted in said receiver for releasably latching said receiver to said barrel jacket when in said closed position and for rotation between a latched and an unlatched position, said latch pin being provided with a flat portion to allow reciprocation of said slide thereover when said latch pin is in said latched position and a semicylindrical portion formed by said flat portion, said semicylindrical portion being positionable to block movement of said slide from said receiver when said latch pin is rotated to the unlatched position and being slidably receivable when in said unlatched position by said slot and rotatably receivable by said cylindrical hole when said latch pin is turned to said latched position whereby said receiver is blocked from opening.

2. A firearm having a barrel jacket, a barrel slidably mounted in said barrel jacket for removal from the front

thereof, a ledge portion extending from the front end of said barrel jacket to assist in jam-free removal of said barrel, a receiver pivotally mounted to said barrel jacket to provide for rearward removal of said barrel and being provided with a slide reciprocable into said barrel jacket, a pair of laterally opposed barrel lock portions provided on the inside of said receiver, each of said barrel locks being provided with an arm portion, and an inwardly projecting lug portion, said lug portion being provided with a front side and a rear side vertical to the longitudinal axis of said receiver, a bottom side and a diagonal portion which forms corner portions at the junction thereof with said rear side and said bottom side of said lug portion, recesses in said barrel for receiving said barrel locks, each of said recesses being provided with a front wall and a rear wall cooperable with said front side and said rear side of the cooperating one of said lugs for locking said barrel to said receiver in battery position, said rear wall being cammingly engageable by said corner portions during pivotal rotation of said receiver from said barrel jacket whereby said barrel is moved rearwardly, cam surfaces extending upwardly and forwardly from said front walls and being engageable by said lug portions during rotation of said receiver to join said barrel jacket whereby said barrel is moved into said battery position to be locked by said barrel locks, and a latch pin mounted in said receiver for releasably latching said receiver to said barrel jacket and being rotatable between a latched and an unlatched position, said latch pin being provided with a flat portion which allows reciprocation of said slide thereover when said latch pin is in the latched position and a semicylindrical portion formed by said flat portion for blocking movement of said slide from said receiver when said latch pin is rotated to the unlatched position.

3. A firearm having a cylindrical barrel jacket, a barrel mounted in said barrel jacket for slidable removal from the front end thereof by the installation of a replacement barrel, a pair of recesses disposed in opposite sides of said barrel, linear walls formed by said recesses, a receiver mounted to said barrel jacket for pivotally unblocking the rear end thereof to permit the installation of said replacement barrel therein from the rear end, and lug means on said receiver cammingly cooperative with said walls for moving said barrel rearwardly in said barrel jacket to an unlocked position during pivoting of said receiver to unlock the rear end of said barrel jacket and forwardly to a locked battery position during pivoting of said receiver to normal position wherein the rear end of said barrel jacket is blocked thereby with said lug means being engageably cooperative with said walls for locking said barrel to said receiver in said battery position.

4. A firearm having a cylindrical barrel jacket, a barrel replaceably mounted in said barrel jacket for slidable removal from the front end thereof by the installation of a replacement barrel therein from the rear, linear cam means disposed on opposite sides of said barrel, a ledge portion extending from the front end of said barrel jacket to provide jam-free removal of said barrel when slidably ejected from said barrel jacket, a receiver mounted to said barrel jacket to pivotally unblock the rear end thereof and permit installation of said replacement barrel from the rear end of said barrel jacket, and barrel locking means in said receiver cooperative with said cam means provided in said barrel for slidably moving said barrel rearwardly in said barrel jacket during pivoting of said receiver to unblock the rear end of said barrel jacket and forwardly during pivoting of said receiver to normal position wherein the rear end of said barrel jacket is blocked thereby and for locking said barrel to said receiver in battery position.

5. A firearm having a cylindrical barrel jacket, a barrel mounted in said barrel jacket for slidable removal from the front end thereof by the installation of a replacement barrel from the rear end of the barrel jacket, a ledge portion extending from the front end of said barrel jacket to

provide jam-free removal of said barrel when slidingly ejected from said barrel jacket, a receiver mounted to said barrel jacket for pivotally unblocking the rear end of said barrel jacket for installation of said replacement barrel into said barrel jacket from the rear end thereof, a 5 pair of opposed barrel locking lugs in said receiver receivable by opposed recesses in said barrel for securely locking said barrel to said receiver in battery position, cam surfaces formed by said recesses, and pivotal portions on said locking lugs cooperable with said cam surfaces for slidably moving said barrel in said barrel jacket toward and away from said battery position responsive to rotation of said receiver.
